UNITED STATES PATENT OFFICE.

GEORGE B. MELENEY, OF CHICAGO, ILLINOIS, ASSIGNOR TO THE LIBRARY BUREAU, OF BOSTON, MASSACHUSETTS.

DESIGN FOR A DESK.

SPECIFICATION forming part of Design No. 33,314, dated October 2, 1900.

Application filed September 10, 1900. Serial No. 29,608. Term of patent 14 years.

To all whom it may concern:

Be it known that I, GEORGE B. MELENEY, a citizen of the United States, and a resident of Chicago, county of Cook, and State of Illinois, have invented and produced a new and original Design for a Desk, of which the following is a specification, reference being had to the accompanying drawing, forming part thereof.

- 10 The drawing is a perspective view of a desk, showing my new design.
- As shown in the drawing, the leading or material feature of my design consists of opposite vertical end supports connected adjacent 15 their lower ends by foot-rails and supporting between their upper ends a body or box-like receptacle having an open top and provided with a back rail and lower front rail, the ends thereof sloping from the back rail to the front 20 rail, and a front inclined outwardly at its upper edge and inwardly at its lower edge and composed of a series of panels side by side.

The end supports a are made up of panel construction and are rectangular in general effect, and the body part a' has an open top a^2 , 25 containing a table a^3 and having a back rail a^4 , front rail a^5 , and sloping ends a^6 , the front of said body part being composed of panels a^7 , placed side by side and inclined inwardly toward their lower end.

The foot-rails a^8 abut at their ends against the supports a and rest on ledges a^9 .

Having described my invention, what I claim as new, and desire to secure by Letters Patent, is—

35 The design for a desk herein shown and described.

In testimony whereof I have signed my name to this specification in the presence of two subscribing witnesses.

GEO. B. MELENEY.
